MINERAL SEPARATOR

Walter R. J. Wock, Auburn, Calif.

Application August 11, 1933. Serial No. 684,685

1 Claim. (Cl. 209—44)

This invention relates to the art of mining machinery and especially to apparatus for the separation of precious minerals and metal bearing sands, such as the so-called black sand and the like, from mineral bearing sands and gravel.

The principal object of the invention is to produce a movable riffle element or analogous structure whereby as the precious metals or metal bearing sands moving through the separator are deposited in the riffles of the riffle element they will be carried away from the separating zone and be washed free of the riffles in a continuous operation. By this step a continuous and uninterrupted operation of separation of the metals and metal bearing sands from the general run of the coarse material may be had, without the necessary shut downs now usual in the operation of stationary sluice boxes in order to allow the periodical clean-up of the separated metals.

A further object of the invention is to produce a mineral separating apparatus having adjustments and instrumentalities whereby the basic assay value of the finally separated minerals may be accurately controlled. This is of importance as in many instances if the percentage of values in the final clean up is kept high profitable operation of low grade sands and gravel may be had since many times the cost of reducing the minerals determines the question of profitable or non-profitable operation of mining properties.

Another object of the invention is to produce a separating apparatus having a large range of capacity with efficiency of operation whether a large or small amount of the initial coarse material is being moved through the same.

Still another object is to provide a combination of mechanisms whereby there may be obtained the advantages of the usual sluice box coupled with those of the method used in hand panning of minerals indulged in by the individual miner or prospector whereby the maximum amount of silt will be removed from the finally separated minerals thus materially building up the basic percentage of values in the final clean up.

A still further object is to produce a simple mechanism which will be inexpensive from the standpoint of both manufacture and operation and which may be readily manufactured for either a portable or stationary installation.

These objects I accomplish by means of such structure and relative arrangement of parts as will fully appear by a perusal of the following specification and claims.

In the drawings similar characters of reference indicate corresponding parts in the several views:

Fig. 1 is a side elevation of my improved separator.

Fig. 2 is a sectional view of a fragmentary portion of that end of the separator into which the original coarse material is delivered and from which the final separated minerals are discharged.

Fig. 3 is a side elevation of a fragmentary portion of the separator showing the end thereof at which the tailings are discharged.

Fig. 4 is a detailed view of an overrunning ratchet clutch used in moving the riffle belt.

Referring now more particularly to the characters of reference on the drawings, the numeral 1 designates a supporting frame for my improved separator which frame may be made up of any desired material appropriately strengthened and supported to effectively carry the parts in the relationship hereinafter described. The numeral 2 designates an inclined sluice box in which may be disposed screening elements and in which is also disposed the traveling riffle belt to be presently described. This member 2 comprises essentially two side plates and a bottom plate, the screens being interposed between the side plates and the movable riffle belt moving over the bottom of the same below the screens.

The sluice box 3 carrying the coarse material usually carried through the medium of a flow of water is mounted above the box 2 and the coarse gravel or sand is carried down this sluice box and the tailings discharged at the lower end thereof in the usual manner.

Adjacent one end of this sluice box 3 is provided a grizzly 4 of any desired mesh but preferably of such size as to deliver all material under one-half inch in diameter down into a chute 5 which in turn delivers into the screen elements disposed in the box 2. Any number of desired screen elements may be arranged in the box 2 in order to progressively screen the fine material containing values from the coarser non-valuable material.

In the present instance I show two screens 6 and 7 disposed one below the other and the materials will screen therethrough as they move through the box 2, the coarse material discharging into the tailing pile at the lower end of the box 2. Below the screens 6 and 7 I preferably provide a pebble flow resistor 8 comprising a top fine mesh screen 8a and a lower coarser mesh screen 8b with fine pebbles 8c interposed between the two screens 8a and 8b. This flow resistor is disposed very closely adjacent the riffle belt which is moving over the bottom of the box 2 and which will be

described in detail later. The function of this resistor is to break up the cataract flow of the water through the separator so as to cause it to flow smoothly and gently over the riffle belt.

5 The box 2 has a pair of spaced flat rails 9 and 10 respectively mounted for reciprocating movement on rollers 11 and 12 respectively mounted in the supporting frame 1.

10 A pair of rigid arms 13 is secured to the sides 10 of the box 2, and mounted in the outer end thereof is a roller 14. A shaft 15 driven from any suitable source of power has mounted thereon a double faced cam 16 cooperating with the roller 14 in order to intermittently impart movement to 15 the box 2 in one direction with the rotation of the cam.

15 Movement of the box 2 in the opposite direction to that imparted by the action of the cam is provided by means of compression springs 17 mounted on the frame 1 and acting against lugs 18 secured to the sides of the box 2 and projecting in the paths of said springs 17. The cam drives the box 2 in one direction against the compression of the springs 17 and the expansion of the springs snaps it back in the opposite direction as the cam moves off of the roller 14. There is thus imparted to the box 2 a vibrating action with the rails 9 and 10 riding on the rollers 10 and 12. The extent of the vibration 30 imparted to the box 2 is determined by the tension of the springs 17 which may be set by an adjustment bolt 19. The return action of the box 2 under the influence of the springs 17 may be cushioned to desired extent by rubber or other 35 resilient bumpers 20 having an adjustment bolt 21 to adjustably fix its position.

40 It will thus be apparent that by reason of this possible vibration of the box 2 the flow of the material over the screens and through the pebble filter will be subject to a severe shaking or vibrating action whereby the relatively heavy metals or metal bearing sands will be effectively precipitated down to the bottom of the box 2. These metals or metal bearing sands having been 45 thus separated from the coarser material which discharges onto the tailing pile at the end of the box 2, I then provide the continuous riffle belt 22 for receiving and finally separating the same, which riffle belt and its cooperating parts are constructed and operate substantially as follows:

50 The riffle belt may of course be of any particular structure which will answer the purpose, but I preferably make the same in the form of a rubber belt having molded therein either concentrated pockets or riffles. In the present instance this belt 22 has formed thereon riffles 23 forming intermediate crevices 24 forming together the riffles for catching the separated minerals. The belt moves over the bottom plate 2a of the box 2 with the riffles facing upward beneath the pebble resistor 8. This resistor 8 functions to 55 smooth out the current flow of the water containing the fine particles of precious metal and thus the precious metals or metal bearing sands 60 will gently settle into the riffles on the belt as it moves along under this pebble resistor. The belt moves in a direction opposite to the movement of the material passing through the box 2 so that the finally recovered minerals are carried 65 by the belt out of the box 2 while the coarser non-valuable material moves in the opposite direction and discharges on the tailing pile at the tail end of the box. The movement of the belt as above described is imparted thereto by 70 means of the following mechanism:

75 A small pinion gear 25 on the shaft 15 meshes with a larger pinion wheel 26 on which is a crank pin 27. A crank shaft 28 extends from the pin 27 and has a pin 29 adjustably mounted in an elongated slot 30 in a ratchet lever 31 turnably mounted on a shaft 32 suitably journaled at a point in the frame 1 adjacent the end of the machine toward which the belt 22 is moving. On the shaft 32 is fixed a ratchet wheel 33. At the upper end of the ratchet lever 31 are pivoted a plurality of overrunning ratchets 34 which engage the ratchet wheel 33 at progressively different points so that with the operation of the ratchet lever an intermittent movement is imparted to the wheel 33. The degree of this movement may be controlled by the adjustment of the pin 29 along the slot 30, thus varying the speed of movement of the ratchet lever 31.

Also fixed to the shaft 32 so as to move in unison with the wheel 33 is a sprocket wheel 35, connected by a driven chain 36 with another sprocket wheel 37 on a shaft 38 supported operatively from the end of the box 2, there being an idler wheel assembly 39 to maintain the tension of the chain 36 as the box 2 vibrates back and forth.

On the shaft 38 is mounted a roller 40 which is the main driving roller for the belt 22 and over which the belt moves down through a chute 41 and under another roller 42 journaled in a frame 2b secured to the box 2; thence over a third roller 43 journaled in the frame 1; and thence under another roller 44 journaled at the opposite end of the box 2 after passing over which the belt 22 commences its travel over the bottom of such box 2.

As the belt 22 passes under the roller 42 it moves through a washing trough 45 which is kept full of water and the accumulated minerals on such belt are cleared from the riffles at this point and may be carried away to a suitable depositary 40 through an outlet pipe 46. Any values falling off of the riffles before they reach this washing trough will fall into the chute 42 and be carried down into the trough, as will be apparent.

In order to thoroughly wash as much silt as possible from the finally separated minerals which have settled into the riffles on the riffle belt 22 I provide ahead of the box 2 a washing mechanism which comprises primarily a pan 47. The bottom of this pan is parallel with and just above the traveling belt 22, and since the belt is moving in an inclined plane, water delivered into the pan 47 through the delivery pipe 48 in finding its own level will leave a body of water 49 in the pan the level of which will be maintained just above the bottom of the pan at its upper end as at 50. This pan 47 is fixed relative to the box 2 so that with the vibration of the box this water will be agitated so that a small portion of it will be continually washed out the open end of the pan at 50 onto the riffles of the traveling belt 22. This action will be similar to the action of washing water from an ordinary miner's pan and will act to clear off accumulated silt from the minerals in the riffles in the belt and carry the same down 55 the inclination of the belt and into the tailing pile. By means of this action a very effective cleaning of the separated minerals may be had whereby the final percentage of values in the final 60 recovered minerals will be materially increased.

It will be obvious from the foregoing description that as the cam 16 cooperating with the spring 17 functions, the entire body of the box 2 carrying the screens, the pebble resistor, and the riffle belt may be vibrated at a high rate of speed,

5 this action giving a highly intensified vibration to the entire separator assembly. This causes the agitation of the coarse material to separate the metals and metal bearing sands therefrom and
 10 also the agitation of the metals and sands in the riffles of the belt. This latter action in turn causes the precious metals and heavier sands to settle into the lowest crevices of the riffles and being there caught or separated from the waste material.
 15 Then, as a final action, the washing of the water from the pan 47 functions to further clean the fine silts from the separated minerals and results in a very high percentage of values being recovered in a most simple, effective and inexpensive manner.

It will be obvious that if the riffle element 22 is not movable in the manner described but was stationary as is usual with most sluice boxes it would only be a matter of a very short time when 20 the riffles therein would be filled up and a shut down of the operation of the machine would be necessary for a clean up. However with my movable riffle belt functioning in the manner described and continuously moving down into the 25 clean up trough 45, the accumulated minerals are cleaned therefrom as fast as they accumulate, the clean belt continuously returning back under the screening and washing mechanism ready to receive further separated minerals.

30 My machine therefore may be operated continuously in a most effective manner which is highly important in connection with hydraulic mining operations where the value bearing gravels or sands are being continuously washed away under hydraulic pressure and where a shut down of the separating means must necessarily require a shut down of the entire mining operations pending the clean up of the minerals required where stationary sluice boxes are used.

35 40 It will be obvious that the various adjustments described for my machine permit me to vary at will the speed of the moving riffles and the violence of the screen agitating means and this

gives me a complete control of proper separation according to the character of the material being fed to the machine and the speed with which it is being fed.

5 While I have described the separator as involving the use of screens, nevertheless the machine is also adapted to operate without any screens, for the purpose of using it instead of a stationary sluice box known as the head box, the purpose of which is to catch all the coarse minerals in which instance the traveling riffle belt would function to continuously discharge the mineral as it accumulated in the riffles.

10 15 From the foregoing description it will be readily seen that I have produced such a device as substantially fulfills the objects of the invention as set forth herein.

20 While this specification sets forth in detail the present and preferred construction of the device, still in practice such deviations from such 25 detail may be resorted to as do not form a departure from the spirit of the invention, as defined by the appended claim.

Having thus described my invention what I claim as new and useful and desire to secure by 25 Letters Patent is:

30 A mineral separator comprising an inclined sluice box, screening elements arranged therein, a riffle belt one run of which is adapted to move through the box under the screening elements, a 35 flushing tank, the other run of the belt being adapted to move through such flushing tank, means to impart vibration to the box and belt, means to impart motion to the belt in the direction of the high end of the box, a water pan on the box at its high end, the uppermost 40 end of the pan being open at a level just above the belt, and means to maintain water in the pan to the level of such open end thereby with the vibration of the pan water will be washed over such end onto the belt.

WALTER R. J. WOOCK.
